The tensile tests were carried out with a Zwick apparatus at $20^\circ \pm 1^\circ$ C. The breaking load (BL) and percentage elongation at break (El., percent) were determined.

These test pieces were aged in a ventilated oven for 5 days at 105° C.

The cables and test pieces corresponding to the following three comparative mixtures were prepared:

- (A) isoctyl phthalate containing 200 p.p.m. of hydrogenated bisphenol-A
- (B) isoctyl phthalate containing 200 p.p.m. of bisphenol-A, and
- (C) isoctyl phthalate not containing any stabilizer.

The following results were obtained:

ELECTRICAL PROPERTIES

	Kilometric resistance (MΩ) at 20° C.			Kilometric resistance (MΩ) at 60° C.		
	Before ageing	Ageing after 5 days	Variation, percent	Before ageing	Ageing after 5 days	Variation, percent
A-----	1,600	1,500	-6.5	25	20	-20
B-----	1,250	550	-56	22	3.7	-82
C-----	1,200	500	-58.5	19	3.5	-81.5

MECHANICAL PROPERTIES

	BL (kg./cm. ²)			El. (percent)		
	Before ageing	Ageing after 5 days	Variation, percent	Before ageing	Ageing after 5 days	Variation, percent
A-----	256	244	-4.5	318	302	-5
B-----	246	183	-25	336	178	-47
C-----	244	185	-24	304	180	-40.5

These results show the distinctly higher resistance to ageing of mixture A containing the stabilizer according to the present invention.

EXAMPLE 2

The same composition as in Example 1 was used, except that isoctyl phthalate was replaced weight for weight by isodecyl phthalate. The operating conditions were similar. In Formula A, the isodecyl phthalate contained 200 p.p.m. of hydrogenated bisphenol-A; in Formula B, it contained 200 p.p.m. of bisphenol-A; in Formula C, it was used alone. The electrical and mechanical measurements, and ageing were carried out as in Example 1.

RESULTS

ELECTRICAL PROPERTIES

	Kilometric resistance (MΩ) at 20° C.			Kilometric resistance (MΩ) at 60° C.		
	Before ageing	Ageing after 5 days	Variation, percent	Before ageing	Ageing after 5 days	Variation, percent
A-----	1,900	1,000	-47.5	18	17.5	-0.5
B-----	1,400	275	-80.5	20	4.9	-75.5
C-----	1,300	250	-80.5	15.5	4.1	-73.5

MECHANICAL PROPERTIES

	BL (kg./cm. ²)			El. (percent)		
	Before ageing	Ageing after 5 days	Variation, percent	Before ageing	Ageing after 5 days	Variation, percent
A-----	264	260	-1.5	349	324	-7
B-----	268	193	-26.5	346	190	-45
C-----	268	201	-25	332	201	-39

EXAMPLE 3

The same composition as in Example 1 was used, except that "Alfol" 8-10 phthalate (trademark) was used as a plasticizer. "Alfols" are linear commercial alcohols obtained by the polymerization of ethylene. The operating conditions were similar. In Formula A, the "Alfol" 8-10

phthalate contained 200 p.p.m. of hydrogenated bisphenol-A; in Formula B, it was used alone. The electrical measurements and ageing were carried out as in Example 1.

RESULTS

	Kilometric resistance (MΩ) at 20° C.			Kilometric resistance (MΩ) at 60° C.		
	Before ageing	Ageing after 5 days	Variation, percent	Before ageing	Ageing after 5 days	Variation, percent
A-----	180	110	-39	4	2.7	-32.5
B-----	160	70	-56	3	0.7	-76.5

EXAMPLE 4

The procedure employed was similar to that of Example 3, but the "Alfol" 8-10 phthalate was treated beforehand with activated alumina, to purify same and improve its electrical properties. The same formulae were compared, A with 200 p.p.m. of hydrogenated bisphenol-A in the plasticizer and B without stabilization of the plasticizer. Electrical measurements and ageing were carried out as in Example 1.

RESULTS

	Kilometric resistance (MΩ) at 20° C.			Kilometric resistance (MΩ) at 60° C.		
	Before ageing	Ageing after 5 days	Variation, percent	Before ageing	Ageing after 5 days	Variation, percent
A-----	220	185	-16	8.8	5.5	-37.5
B-----	200	140	-30	4.9	2.1	-57

EXAMPLE 5

The same composition was used, except that 2-ethylhexyl phthalate was used as the plasticizer; the procedure followed was similar. In Formula A, the 2-ethylhexyl phthalate contained 200 p.p.m. of hydrogenated bisphenol-A; in Formula B it contained 200 p.p.m. of bisphenol-A; in Formula C, it was used alone. Electrical measurements and ageing were carried out as in Example 1.

RESULTS

	Kilometric resistance (MΩ) at 20° C.			Kilometric resistance (MΩ) at 60° C.		
	Before ageing	Ageing after 5 days	Variation, percent	Before ageing	Ageing after 5 days	Variation, percent
A-----	1,500	-----	-----	10.5	6	-43
B-----	1,400	-----	-----	8	5	-37.5
C-----	1,300	-----	-----	6.5	5	-23

EXAMPLE 6

The following formulation was used:

Parts
CPV ("Lucovyl" DS 1300) ----- 62
2-ethylhexyl sebacate ----- 16.5
2-ethylhexyl phthalate ----- 15.5
Lead stabilizers ----- 3
Fillers ----- 3.7

In the first case (A) the 2-ethylhexyl sebacate and 2-ethylhexyl phthalate both contained 200 p.p.m. of hydrogenated bisphenol-A; in the second case (B), they contained 200 p.p.m. of bisphenol-A; in the third case (C), they contained 3% of trinonylphenyl phosphite. The procedure followed was similar to and the electrical

measurements and ageing were carried out as in Example 1.

RESULTS

ELECTRICAL PROPERTIES

	Kilometric resistance (MΩ) at 20° C.			Kilometric resistance (MΩ) at 60° C.		
	Before ageing	Ageing after 5 days	Vari- ation, percent	Before ageing	Ageing after 5 days	Vari- ation, percent
A-----	700	615	-12	4.8	4.7	-2
B-----	650	550	-15	4.5	3.8	-15.5
C-----	570	275	-51.5	4.2	2.5	-40.5

EXAMPLE 7

Methylhexyldi - (4 - hydroxycyclohexyl)-methane was used in an amount of 200 p.p.m. in the plasticizer instead of hydrogenated bisphenol-A, according to the conditions set forth in Example 1. Increased resistance to ageing according to the evolution of the mechanical properties was observed.

EXAMPLE 8

500 p.p.m., in relation to the plasticizer, of dimethyldi-(2,6-dimethyl-4-hydroxycyclohexyl)-methane were used instead of hydrogenated bisphenol-A, according to the conditions of Example 1, with a similar increase in the resistance to ageing.

What we claim is:

1. A stabilized resinous composition comprising (a) a chlorine-containing vinyl resin, (b) a biscyclohexanol of the formula:

wherein R_1 and R_2 are hydrogen or alkyl radicals containing from 1 to 18 atoms, R_3 and R_4 are hydrogen or alkyl radicals containing from 1 to 4 carbon atoms and m and n are integers from 1 to 4 and (c) at least one substance selected from the group consisting of tribasic lead sulfate, dibasic lead phthalate and dibasic lead phosphite.

2. A composition according to claim 1 in which the biscyclohexanol is isopropylidene-4,4'-biscyclohexanol.

3. A composition according to claim 1 in which the biscyclohexanol is isobutylidene-4,4'-biscyclohexanol.

4. A composition according to claim 1 in which the biscyclohexanol is methylhexyldi-(4-hydroxycyclohexyl)-methane.

5. A composition according to claim 1 in which the biscyclohexanol is hexyldi - (4 - hydroxycyclohexyl)-methane.

6. A composition according to claim 1 in which the biscyclohexanol is dimethyldi - (2,6-dimethyl-4-hydroxycyclohexyl)-methane.

7. A composition according to claim 1 in which the biscyclohexanol is di - (2,6-di-tert.-butyl-4-hydroxycyclohexyl)-methane.

8. A composition according to claim 1 in which the amount of the biscyclohexanol in the composition is from 20 to 20,000 parts per million based on the weight of the chlorine-containing vinyl resin.

9. A stabilizing composition for a chlorine-containing vinyl resin which comprises a biscyclohexanol of the formula:

wherein R_1 and R_2 are hydrogen or alkyl radicals containing from 1 to 18 carbon atoms, R_3 and R_4 are hydrogen or alkyl radicals containing from 1 to 4 carbon atoms and m and n are integers from 1 to 4 and at least one substance selected from the group consisting of tribasic lead sulfate, dibasic lead phthalate and dibasic lead phosphite.

10. A composition according to claim 9 in which the biscyclohexanol is isopropylidene-4,4'-biscyclohexanol.

11. A composition according to claim 9 in which the biscyclohexanol is isobutylidene-4,4'-biscyclohexanol.

12. A composition according to claim 9 in which the biscyclohexanol is methylhexyldi-(4-hydroxycyclohexyl)-methane.

13. A composition according to claim 9 in which the biscyclohexanol is hexyldi - (4 - hydroxycyclohexyl)-methane.

14. A composition according to claim 9 in which the biscyclohexanol is dimethyldi-(2,6-dimethyl-4-hydroxycyclohexyl)-methane.

15. A composition according to claim 9 in which the biscyclohexanol is di-(2,6-di-tert.-butyl-4-hydroxycyclohexyl)-methane.
